UNITED STATES PATENT OFFICE.

SIMON MYERSON, OF CAMBRIDGE, MASSACHUSETTS.

BACKING FOR ARTIFICIAL TEETH.

Application filed December 15, 1925. Serial No. 75,494.

This invention relates to a backing for an artificial tooth, known in dental parlance as a dummy, and used to replace a lost natural tooth, the dummy being provided with pins 5 projecting from its posterior face and inserted in sockets located within a portion of a metallic bridge.

The object of the invention is to provide a metal backing permanently attachable to 10 the bridge during the operation of making the latter, and constituting, when attached, a fixture which includes a rigid tooth seat and rigid-pin-receiving sockets, each immovable relative to the bridge, the backing having 15 metallic surfaces complementary to those of the posterior face and pins of the tooth, and adapted to be secured thereto by cement, so that a dummy may be conveniently secured to the bridge, and a broken dummy 20 may be removed and replaced by another, the rigidity of the metallic socket walls incorporated in the bridge, rendering said walls free from liability of deformation, so that they cannot be closed or distorted, and 25 are always in condition to receive the pins, whether of an original dummy, or of a dummy substituted for a broken one.

I have shown the backing adapted for use with a tooth having a root extension, but 30 it will be obvious that it may be adapted for use with other types of pin teeth.

Of the accompanying drawings forming a part of this specification,—

Figure 1 shows in perspective a backing 35 embodying the invention, adapted for use with a tooth or dummy of the type referred to.

Figure 2 is a longitudinal section of the 40 backing.

Figure 3 shows in perspective a tooth applicable to the backing shown by Figure 1.

Figure 4 is a longitudinal section of the 45 tooth shown by Figure 3.

Figure 5 shows the backing as in Figure 2, and the tooth as in Figure 4, and shows by dotted lines a bridge to which the backing is secured when in use.

Figure 6 shows in perspective a partly 50 completed backing.

The drawings show the parts much enlarged.

The same reference characters indicate the 55 same parts in all of the figures.

My improved backing comprises a thin plate 12, preferably of gold, having an outer

side conforming to the posterior face 13, of an artificial tooth or dummy, from which pins 14 project, an inner side formed to bear on a bridge 15, and an integral rib 16, projecting from the inner side and containing 60 sockets 17, opening on the outer side, and adapted to receive the pins 14. The surfaces of the inner side and rib are adapted to be attached and adhere to the metallic material of the bridge 15, the latter being cast on or soldered to said surfaces. The backing when thus attached, constitutes a fixture on the bridge, and its outer side and socket walls are attachable by cement to the 65 posterior face and pins of the tooth.

To minimize the quantity of metal employed in the backing, the length of the rib 16 may be less than the width of the plate 12, as shown by Figure 1, or the midlength portion of the rib may be interrupted by a 70 recess, as shown by Figure 6, which shows the backing partly completed.

The plate 12 may be bent to conform its outer side to the two faces forming a recess in a tooth of the character referred to, although, if desired, the bend may be omitted so that the plate will conform to a posterior face which is flat from end to end of the tooth.

The backing may be marketed in the form 85 shown by Figure 6, its area being greater than that of the posterior face, so that a dentist may cut away the surplus marginal material in exact conformity to the margin of the tooth face.

The backing may be formed by suitable dies, adapted to form the external surfaces and the sockets, or the sockets may be formed by drilling, or otherwise.

It will be seen that a dentist, supplied 90 with the described backing, may readily incorporate the same as a fixture on a bridge by well known methods not requiring description, and that the pin sockets of the incorporated backing are non-distortable, and 100 are securely embedded in the bridge material.

In practice the bridge 15 is secured by well known means to natural teeth at opposite ends of a gap caused by the removal 105 of one or more intermediate natural teeth. One or more backings may be secured to the bridge, according to the number of natural teeth to be replaced. When the tooth or dummy is of the type referred to, its root 110

portion 20 enters the cavity in the gum 21 (Figure 5) from which the root of a natural tooth has been removed.

I claim:

- 5 An artificial tooth backing comprising a thin metal plate having an integral relatively thick elongated rib projecting from and extending transversely of its inner face, and

provided with pin receiving sockets that open through the outer face of the plate, ¹⁰ said rib preventing warping of the backing plate transversely.

In testimony whereof I have affixed my signature.

SIMON MYERSON.
